UNITED STATES PATENT OFFICE.

ISRAEL FISHER, OF NEW YORK, N. Y., ASSIGNOR OF ONE-HALF TO
ABRAHAM FISHER, OF SAME PLACE.

DESIGN FOR FABRIC.

SPECIFICATION forming part of Design No. 31,056, dated June 20, 1899.

Application filed May 25, 1899. Serial No. 718,305. Term of patent 7 years.

To all whom it may concern:

Be it known that I, ISRAEL FISHER, of the city of New York, borough of Manhattan, in the county of New York and State of New York, have invented and produced a new and original Design for Fabric, of which the following is a full, clear, and exact description.

Reference is to be had to the accompanying drawing, forming a part of this specification, in which the figure represents a fabric design embodying my invention.

The design is particularly adapted for a table or bed spread centerpiece, and the leading feature, as shown in the drawing, consists of a number of mounted officers and foot soldiers in marching order, with standard-

bearers in the lead, one carrying an American flag and the other carrying a Cuban flag.

Referring particularly to the drawing, the commanding officer represents General Maximino Gomez and is shown at about the center of the design, and this commanding officer is illustrated as saluting. The background is formed by foliage, and in this background a number of people are shown, and in the distance is the representation of a building.

I claim—

The design for fabric herein shown and described.

ISRAEL FISHER.
